UNITED STATES PATENT OFFICE.

HENRY L. HASKELL, OF LUDINGTON, MICHIGAN, ASSIGNOR TO CARROM-ARCHIARENA COMPANY, OF LUDINGTON, MICHIGAN.

POOL-TABLE.

No. 853,636.

Specification of Letters Patent.

Patented May 14, 1907.

Application filed December 18, 1903. Serial No. 185,706.

To all whom it may concern:

Be it known that I, HENRY L. HASKELL, a citizen of the United States, residing at the city of Ludington, county of Mason, State of Michigan, have invented certain new and useful Improvements in Pool-Tables, of which the following is a specification.

This invention relates to improvements in pool tables.

10 An object of this invention is to provide an improved pool table adapted to deliver the balls pocketed in the several pockets into a common receptacle.

Another object is to provide an improved 15 pool table adapted to deliver the balls pocketed in the several pockets into a common receptacle, which is economical to produce and attractive in appearance, and one which does not add materially to the weight of the 20 table.

Further objects, and objects relating to structural details, will definitely appear from the detailed description to follow.

I accomplish the objects of my invention 25 by the devices and means described in the following specification.

The invention is clearly defined and pointed out in the claims.

A structure embodying the features of my 30 invention is fully illustrated in the accompanying drawing forming a part of this specification, in which—

Figure 1 is a plan view of a structure embodying the features of my invention, portions of the table bed being broken away to show the arrangement of parts. Fig. 2 is a detail cross-sectional view taken on a line corresponding to line 2—2 of Fig. 1. Fig. 3 is an enlarged detail sectional view taken on a 35 line corresponding to line 3—3 of Fig. 1. Fig. 4 is a detail inverted plan view of the delivery chute D showing its arrangement. Fig. 5 is a plan view of a modified construction of my improved pool table, portions of 40 the table bed being broken away to show the arrangement of parts.

In the drawing, the sectional views are taken looking in the direction of the little arrows at the ends of the section lines, and similar letters of reference refer to similar parts 45 throughout the several views.

Referring to the drawing, A represents the frame, upon which the bed of the table A' is supported.

The pockets B are open at the bottom and 55 deliver to the ball conveyer C. This ball receiver or conveyer C is formed of canvas, or other suitable fabric, and is arranged under the bed of the table so that it is common to all the pockets. The receiver or conveyer C 60 is so shaped that the balls delivered thereto from the pockets all travel to the central delivery opening c. This opening c delivers to a chute D, which, in turn, delivers the balls to a suitable ball receptacle E at the side of 65 the table. The conveyer C is formed of canvas or other suitable fabric preferably cut in triangular pieces, and secured together by suitable means.—Cords c' are sewed into the 70 seams, as clearly appears in Fig. 4.

A suitable ring is secured about the central opening and the cords c' are secured to this ring and to the table frame, thus applying proper tension, so that the balls will travel rapidly to the delivery point. 75

The chute D is secured to the conveyer C by suitable bolts or rivets.—This arrangement retains the chute in the proper position, and also serves to apply tension to the conveyer C so that it is kept taut. 80

In the modified construction shown in Fig. 5, the delivery opening c of the conveyer C is arranged at one end of the table to deliver directly to the ball receptacle.—This arrangement has the advantage of dispensing 85 with the trough D.

I have illustrated my invention as applied to a four pocket table. It is evident, however, that it is equally applicable to a six-pocket table. 90

I desire to remark that my invention is capable of considerable structural variation.—If desired, the pockets B may be omitted and the conveyer C arranged to take the balls directly from the pocket openings in the table 95 bed. Other variations will readily appear to those skilled in the art to which my invention relates.

My improved billiard or pool table is very economical to produce, is attractive in appearance, and light in weight.—My table is also of advantage in that the balls are delivered to the receptacle E in a practically noiseless manner. Other advantages are apparent. 100

Having thus described my invention, what I claim as new and desire to secure by Letters Patent is— 105

1. In a pool table, the combination of a suitable frame and bed having pocket openings; a sheet-like ball conveyer common to all of said pocket openings and consisting of suitable fabric, having a suitable delivery opening, supported beneath said bed; a ring about said delivery opening; cords attached to said fabric and secured to said frame near said pocket openings and to said ring; a delivery chute secured to said ball conveyer in position to receive the balls from said delivery opening; and a ball receptacle, for the purpose specified. 25
2. In a pool table, the combination with a frame and a bed having pocket openings therein, a sheet-like ball conveyer of suitable fabric arranged under said bed so as to embrace all of said pocket openings, said conveyer having a suitable delivery opening 30 therein; cords secured to said fabric extending from points adjacent from said pockets to said delivery opening, for applying tension to said fabric, for the purpose specified. 35
3. In a pool table, the combination of a suitable frame and bed having pocket openings; a ball conveyer common to all of said pocket openings and consisting of suitable fabric, having a suitable delivery opening, supported beneath said bed; a ring about said delivery opening; cords attached to said fabric and secured to said frame near said pocket openings and to said ring; and a ball receptacle, for the purpose specified. 40
4. In a pool table, the combination with a frame of a bed having pocket openings 35 therein; a ball conveyer comprising a sheet of suitable fabric arranged under said bed so as to embrace all of said pocket openings, said conveyer having a suitable delivery opening therein. 40

In witness whereof, I have hereunto set my hand and seal in the presence of two witnesses.

HENRY L. HASKELL. [L. s.]
